UNITED STATES PATENT OFFICE.

HORACE FALK NEUMAYER, OF MACUNGIE, PENNSYLVANIA.

FUEL SAVER AND DECARBONIZER.

Application filed January 13, 1923. Serial No. 612,534.

To all whom it may concern:

Be it known that I, HORACE F. NEUMAYER, a citizen of the United States, residing at Macungie, in the county of Lehigh and State of Pennsylvania, have invented new and useful Improvements in Fuel Savers and Decarbonizers, of which the following is a specification.

My invention relates to a fuel saver and decarbonizer which is adapted to be attached to the intake pipe of an internal combustion engine between the carburetor and the manifold.

The general object of the invention is to provide a device through which air may be drawn into the fuel mixture, and in which the air, while passing therethrough, will be charged with certain compounds that will render the combustion of the fuel more complete and decrease the amount of carbon which will be deposited in the cylinders.

The invention is particularly adapted to contain camphor or moth balls by which the air, as it passes through the device, becomes camphorated, and not only increases the power which will be obtained from a given amount of gasoline, but also to a considerable degree prevents the adherence and lodgment of the particles of carbon upon the walls of the firing chamber.

The device is also adapted to be used for introducing moisture into the cylinders, and it has been found that whenever the cylinders become covered with carbon, a small amount of water, usually about one-half pint, introduced slowly by means of my invention while the engine is running, will dislodge carbon and make it unnecessary to go through the laborious process of removing the cylinder heads and scraping out the carbon.

The preferred form of the invention is illustrated in the accompanying drawing, in which:

Fig. 1 is a front elevation of the device attached to the intake manifold of the engine.

Fig. 2 is a vertical longitudinal section.

Referring in detail to the drawing, the invention comprises a nipple 5 which is threaded into a hole tapped into the intake pipe 6 between the manifold 7 and the carburetor 8, as shown in Fig. 1. The outer end of the nipple is connected with a T-shaped coupling 9, to the other end of which is connected a nipple 10 which is in commun-

nication with a depending cylindrical casting 11 provided at its lower end with a threaded plug 12 having a central atmospheric port 13 through which air may be drawn by suction of the engine while running.

The coupling 9 has a partition 14 extending across its central portion and having an intermediate portion 15, which extends longitudinally of the coupling at right angles to the direction of the stem 16, and having a port therethrough which is controlled by the valve 17. The stem 16 of the coupling has a plug 18 in its outer end through which extends a threaded stem 19. The valve is provided with a cup-shaped stem 20 within which is a coiled spring 21 that acts between the inner end of the stem 19 and the valve to hold the latter normally seated. The stem 19 may be adjusted within the plug 18 to adjust the tension of the spring 21, and may be locked in its adjusted position by means of a lock nut 22. The stem 19 should be so adjusted that when the engine is idling, no air will pass the valve 17, but when the speed of the engine increases to more than five miles an hour, the valve will open and the amount of air passing therethrough will vary with the speed of the engine.

The cylindrical chamber 11 is provided near its upper end with an interior flange 23, on the under side of which is seated a screen 24 that covers the opening 25 through which the air must pass in entering the intake pipe. The chamber 11 is long enough to contain two or more camphorated balls 26, the diameter of the balls being somewhat less than the interior diameter of the chamber, so that they may move freely therein and the lowermost ball is normally seated upon and covers the port 13. When the air is drawn in by the suction of the engine, the balls 26 will be readily raised and will rub together and rotate, thus causing camphor to be taken up by the air and drawn into the cylinders. The screen 24 will act not only as an abutment for the balls, but will strain the air and prevent dirt from being drawn in.

The increased amount of air thus supplied to the engine cylinders results in a saving of fuel, and the saturation of air with camphor, reduces the amount of carbon which will be formed on the walls of the cylinder. It will be understood, however, that compounds other than camphor balls

may be used with good results, and in fact, a sponge containing water may be inserted in the cylinder 11, and the moisture thus supplied will result in a more complete combustion, especially when low grade fuel is used, and will thereby prevent the formation of carbon deposits.

It may, however, be found in the course of time that carbon will accumulate in the cylinders, and whenever this is the case, the cylinder 11 may be revolved so as to extend upwardly from the nipple 10, and a small amount of water may then be slowly poured into the port 13 while the engine is running. This will result in dislodging the carbon and removing the same from the cylinders in a few minutes without scraping.

While I have shown and described the preferred structure of my invention, it will be understood that various modifications may be made therein without departing from the spirit of the invention. The device may also be used in other relations wherever it is desired to charge a stream of air with chemicals.

What is claimed is:—

1. The combination with the fuel intake pipe of an internal combustion engine, of an auxiliary air inlet connected thereto and having a chamber containing camphor balls, said chamber being located between the auxiliary inlet and the atmosphere and having an atmospheric port at its lower end which is normally closed by one of the camphor balls seated thereon, said camphor ball acting as a valve for the atmospheric port adapted to be opened by the suction of the engine.

2. The combination with the fuel intake pipe of an internal combustion engine, of an auxiliary air inlet passage having a chamber containing camphor balls, a spring-held valve normally closing the passage between the chamber and the intake pipe, means for adjusting the tension of said spring, said chamber having a screen across its upper end between the camphor balls and the valve, and an atmospheric port at the lower end of the chamber, one of the balls being normally held by gravity in a position covering the port.

3. The combination of a pipe having a cylindrical chamber in communication with one end and depending therefrom, a plurality of camphorated balls in the chamber, said balls having a diameter slightly less than the internal diameter of the chamber, a port at the lower end of the chamber, the lowermost ball normally resting upon and covering said port, said balls being adapted to be raised and rotated by a current of air passing through the port and through the passageway.

4. The combination of a pipe having a

cylindrical chamber connected with its inlet end and depending therefrom, a screen extending across the upper portion of the chamber below the pipe, an inlet port at the lower end of the chamber, a plurality of camphor balls within the chamber and of slightly less diameter than the internal diameter of the chamber, the lowermost ball normally resting on and covering said port, a valve interposed in the pipe, a spring normally closing said valve, the valve being operable by suction applied at the outlet end of the pipe to permit a current of air to pass through the chamber and to raise and rotate the camphor balls.

5. The combination of a pipe line having a chamber connected with one end adapted to contain a compound for saturating air passing therethrough, a valve chamber interposed in the pipe line and comprising a coupling having a partition across its interior, a portion of the partition extending longitudinally and having a port therethrough, a valve stem extending radially from the coupling and having a valve adapted to cover said port, a spring holding said valve normally closed, and a stem threaded into the coupling in alignment with the valve stem and spring and adjustable to vary the tension of the latter.

6. The combination with the fuel intake pipe of an internal combustion engine, of an auxiliary air inlet connected thereto and having a chamber containing a partially volatile decarbonizing compound in globular form, said chamber being located between the auxiliary inlet and the atmosphere, and having an atmospheric port at its lower end which is normally closed by one of the globular forms seated thereon, said globular form acting as a valve for the atmospheric port adapted to be opened by the suction of the engine.

7. The combination with the fuel intake pipe of an internal combustion engine, of an auxiliary air inlet connected thereto and having a chamber containing a partially volatile decarbonizing compound in globular form, said chamber being located between the auxiliary inlet and the atmosphere, and having an atmospheric port at its lower end which is normally closed by one of the globular forms seated thereon, said globular form acting as a valve for the atmospheric port adapted to be opened by the suction of the engine, said chamber having a threaded connection with the auxiliary inlet, whereby it may be inverted and water poured through said port.

8. The combination with the fuel intake pipe of an internal combustion engine, of an auxiliary air inlet connected thereto and having a chamber containing a partially volatile, decarbonizing compound in globular form, said chamber being located between

the auxiliary inlet and the atmosphere, and having an atmospheric port at its lower end which is normally closed by one of the globular forms seated thereon, said globular form acting as a valve for the atmospheric port adapted to be opened by the suction of the engine, a spring held valve normally closing the inlet passageway to form increased resistance to the suction there-through, and means for adjusting the tension of the spring. 10

In testimony, that I claim the foregoing as my own, I have hereto affixed my signature.

HORACE FALK NEUMEYER.
